US0D1089850S

(12) United States Design Patent (10) Patent No.: US D1,089,850 S
(45) Date of Patent: * Aug. 19, 2025

(54) FOOT FILE

(71) Applicant: Abraham Menasche, Pembroke Pines, FL (US)
(72) Inventor: Abraham Menasche, Pembroke Pines, FL (US)

() Term: 15 Years

(21) Appl. No.: 29/894,620

(22) Filed: Jun. 12, 2023

(51) LOC (15) Cl. 28-03

(52) U.S. Cl.

USPC D28/59

(58) Field of Classification Search

USPC D28/4, 9, 56, 57, 58, 59, 61, 62, 99

CPC A61Q 3/00; A45D 29/00; A45D 29/18;

..... A45D 2200/1054; A47K 7/026

(57) CLAIM

The ornamental design for a foot file as shown and described.

DESCRIPTION

FIG. 1 is a front-top perspective view illustrating my design for a foot file;

FIG. 2 is a front view thereof;

FIG. 3 is a right side view thereof;

FIG. 4 is a top view thereof;

FIG. 5 is a left side view thereof;

FIG. 6 is a bottom view thereof; and,

FIG. 7 is a rear view thereof.

1 Claim, 7 Drawing Sheets
